MANHOLE GUARD

Wilbur W. Stevenson, Pittsburgh, Pa.

Application March 24, 1944, Serial No. 527,906

9 Claims. (Cl. 160—210)

The invention relates to manhole guards, by which is meant structures that are placed around and above street manholes to protect men working in them against injury by articles that may fall into the holes, and to protect street traffic such as pedestrians and vehicles against injury by reason of open manholes.

An object of the invention is to provide a sturdy manhole guard formed of sections which may readily be assembled for use and disassembled for transportation or for storing in a manhole throughout the night, and which when assembled forms a rigid structure that may be firmly attached to a manhole casing to afford full protection, the guard being provided with a gate which is easily operable by workmen entering and leaving a manhole.

A further object is to provide a screen adapted to be associated with the guard for closing the top of the manhole to protect workmen against stones or other missiles that might enter the top of the guard, the screen being readily closed and opened by a workman entering and leaving the manhole.

The preferred embodiment of my invention is illustrated in the accompanying drawings of which Fig. 1 is a plan view of the manhole guard with the gates shown in full lines in their closed and in dotted lines in their open positions; Fig. 2 is an elevation thereof; Fig. 3 is a sectional view of the base of the guard, the plane of view being indicated by the line III—III, Fig. 2; Fig. 4 is a similar sectional view of the base showing its attachment to a manhole casing, the plane of view being indicated by the lines IV—IV on Figs. 1 and 2; Fig. 5 an elevation of an upright forming a part of the superstructure of the guard; Fig. 6 a detailed vertical sectional view of a post forming part of a gate section, the plane of view being indicated by the line VI—VI, Fig. 2; and Fig. 7 a plan view of a screen adapted to be associated with the guard base which is shown in dotted lines.

The manhole guard comprises essentially a base 1 and a superstructure 2, each formed of a plurality of separable parts adapted to be telescopedically assembled. As it is shown in Fig. 1, the base is formed of two like semi-circular sections, each including a semi-circular pipe 4 adapted to rest on the surface of a street surrounding a manhole, and a semi-circular toe board 5 whose lower edge is welded to the outside of pipe 4. One end of pipe 4 is provided with a dowel pin 6, Fig. 1, adapted to be received by the open end of the like pipe of the other sec-

tion. Also, each base section is provided with four sockets 7 in the form of short sections of pipe whose lower ends are welded to the top face of pipe 4. Each of these sockets is adapted to receive an upright section of the superstructure of the guard which will presently be explained, the sockets being spaced at equiangular distances of 45 degrees for receiving eight uprights to form an octagonal superstructure.

For securely attaching the base of the guard to an annular casing that forms the upper wall of a manhole, each base section is provided with inwardly extending lugs 10 in the form of plates which are welded to the top of circular pipes 4, the lugs being spaced at equal intervals when the sections of the base are assembled. As shown in Fig. 4, a manhole casing 11 is provided with a sturdy bolt 12 below each lug 10. Engaging the shank of bolt 12 there is an upwardly extending adapter link 13 whose lower end is provided with a keyhole slot having its enlarged end uppermost to receive the head of the bolt. The upper end of link 13 is provided with a horizontally extending flange 14 having a vertical opening for receiving the smooth portion of a threaded bolt 15 which extends upwardly through an opening formed in lug 10. The upwardly projecting end of bolt 15 is provided with a hand nut 16 whose lower face engages the top of lug 10, firmly to anchor the base when all the nuts 16 are thus tightened.

When the sections of base 1 are thus attached to a manhole casing, toe board 5 prevents stones or other missiles rolling on the street from entering the manhole. To prevent street surface water from flowing into the manhole, the bottoms of tubes 4 may be sealed to the tops of casing 11 by a suitable plastic compound as indicated at 17 in Fig. 4, and the meeting vertical edges of toe boards 5 may be sealed by adhesive tape.

The superstructure comprises eight uprights, six of which are of the same form as the upright 20 shown in Fig. 5, and two of which that form gates are similar to upright 20 but differ in details that will presently be explained. Each upright 20 comprises a vertical post 21 in the form of a pipe, and an upwardly inclined beam 22 in the form of a pipe whose inner end is welded to the top of post 21 and to whose outer end there is welded a downwardly extending pin 24 which may be a short section of a pipe. Between beam 22 and post 21 there is a sheet metal flag 25 whose ends are welded to the beam and post. The exposed face of this flag may be painted red to indicate danger, and it may be provided with

a cube corner reflector 26 to warn approaching automobilists of the presence of the manhole guard.

One of the gate sections, namely, that shown at 30 in Figs. 1 and 2, is the same as upright 20 with the exception that the outer end of beam 22 of gate section 30 is provided at its lower side with a short pipe 31 which is welded to the beam. Within the confines of pipe 31 the lower face of beam 22 is perforated to receive a locking bolt of the other gate section presently to be explained.

In assembling superstructure 2 upon base 1, the lower end of post 21 of gate section 30 is inserted in one of the tubular sockets 7 of the base. Thereafter, proceeding in a clockwise direction as shown in Fig. 1, the six like uprights 20 are similarly placed successively on the base, each post of an upright being received by a socket 7, and the downwardly extending pin 24 at the outer end of beam 22 of each upright being telescopically received by the upper end of the tubular post previously positioned.

The last upright of the structure to be assembled is gate section 35, whose construction will now be explained. As shown in Fig. 2, gate section 35 is formed of a tubular post 36 whose lower end terminates above the top of the toe board 5 of the base so that the gate section may swing outwardly. Beam 37 of the gate section 35 is provided at its outer end with a long tubular pin 38 which is received by post 21 of the last of uprights 20 to be positioned upon base 1. The upper end of pin 38 is provided with a laterally extending collar 39 which bears upon the top of post 21 in which the pin is inserted, the construction being such that pin 38 lying in post 21 acts as the pintle of a hinge pivotally to support gate section 35.

As shown in Fig. 6, post 36 of gate section 35 is provided with a vertically movable locking bolt 40 which may be tubular in form and which is positioned within and guided by a tube 42 arranged concentrically within post 36 and suitably welded to it at its upper end. The lower end of locking bolt 40 is provided with a latch 43 which extends through an inverted J-shaped slot 44 formed in the portion of the wall of post 36 that faces the interior of the guard so that latch 43 may be operated by a workman within the guard and is not readily discernible by anyone outside of the guard. When the gate is unlocked, latch 43 lies at the lower end of the longer stem of slot 44.

When the two sections of base 1 have been assembled as shown in Figs. 1 and 2 and attached to a casing 11 of a manhole as shown in Fig. 4, workmen may enter the manhole guard through gate sections 30 and 35 which are then open to their dotted line positions shown in Fig. 1. A workman then swings the gate sections to their closed position shown in full lines in Fig. 1 and brings bolt 40 of gate section 35 into registry with tube 31 on beam 22 of gate section 30. The workman then lifts latch 43 to cause its upper end to engage the opening in the bottom of beam 22 of gate section 30 and turns latch 43 so that it lies in the shorter portion of slot 44, in which position the gates are locked. The manhole guard then forms a sturdy rigid structure which protects both workmen and pedestrians.

To disassemble the guard it is only necessary to lift the gate sections 30 and 35 and the uprights 20 from the sockets 7 of the base, to loosen hand nuts 16 to release adapter links 13 from

their engagement with stud bolts 12, and to separate base sections by moving them laterally from each other. The thus separated parts of the superstructure and base are light and easily handled. Furthermore they are of such relatively small size that at the end of a work day they may be stored in a manhole over night.

An advantage of the guard is that when it is assembled and connected to a manhole casing it forms a sturdy structure that is capable of withstanding heavy external impacts without being moved or distorted. Also, the gate sections 30 and 35 have the same external appearance as the uprights 20, and hence are not readily discernible by curious or malicious pedestrians who might tamper with or open the gates.

To protect workmen in a manhole against stones or missiles that may fall or be thrown into the top of a manhole guard, the top of the hole may be protected by a screen of the form shown in Fig. 7. This screen comprises a plate 50 which is provided with a pair of openings 51 adapted to receive adjacent sockets 7 of base 1. To plate 50 there is pivotally connected a three-part screen having a central section 52 and a pair of outer or wing sections 53. The central section is formed of a U-shaped rod 54 whose ends are provided with eyes that engage holes in plate 50, and a protecting screen attached to the rod. Each wing section 53 is also formed of a U-shaped rod 55 whose ends are provided with eyes for pivotally mounting it on rod 54, the space within each rod 55 being provided with a protecting screen.

When the screen is assembled with the manhole guard its wings 53 are folded upon central section 52 and the latter is swung upwardly to a side of the guard. The last workman to enter a manhole pulls the screen down after him, and, reaching over the sides of the screen, swings wings 53 to their horizontal position. The central portion of the screen is held in its horizontal position by its engagement with the tops of hand nuts 16, and wings 53 may be held in their horizontal positions by lugs 56 attached to and extending inwardly from tubes 4 of base 1. When workmen leave a manhole, the screen may readily be opened by first folding wings 53 upon central section 52, and then swinging the latter upwardly.

According to the provisions of the patent statutes, I have explained the principle and operation of my invention, and have illustrated and described what I now consider to be the best embodiment of it. However, I desire to have it understood that, within the scope of the appended claims, the invention may be practiced otherwise than specifically illustrated and described.

I claim:

1. A manhole guard comprising a continuous base formed of a plurality of separable parts, directly connected to each other, and a plurality of separable uprights removably supported by the base and removably connected directly to each other to form an enclosure, at least one of said uprights being pivotally mounted to form a gate.

2. A manhole guard comprising a base formed of a pair of like separable parts telescopically assemblable with each other to form a continuous support, and a superstructure comprising a plurality of separable uprights removably supported by the base and removably connected directly to each other to form an enclosure, at least one of said uprights being pivotally mounted to form a gate.

3. A manhole guard comprising a base formed of a pair of telescopically assemblable sections

each comprising a pipe of semi-circular, shape and a semi-circular toe board attached to the pipe, and a plurality of separable uprights removably supported by the base and removably connected to each other to form an enclosure, at least one of said uprights being pivotally mounted to form a gate.

4. A manhole guard comprising a continuous base formed of a plurality of separable parts directly connected to each other and provided with vertically disposed sockets, and a plurality of uprights each including a post adapted to be telescopically received by one of said sockets, each of said uprights being detachably connected directly to an adjacent upright, and at least one 15 of said uprights being pivotally mounted to form a gate.

5. A manhole guard comprising a base formed of a plurality of separable parts provided with vertically disposed sockets, and a plurality of uprights each including a post whose lower end is telescopically positioned in one of said sockets, each upright including an upwardly inclined beam having a pin at its outer end telescopically positioned in the post of an adjacent upright, and a gate section pivotally supported by one of said uprights.

6. A manhole guard comprising a base formed of a plurality of separable parts provided with vertically disposed sockets, a plurality of uprights each formed of a tubular post whose lower end is telescopically positioned in one of said sockets and of an upwardly inclined tubular beam having a pin in its outer end telescopically posi-

tioned in the post of an adjacent upright, and a gate section pivotally supported by one of said uprights.

7. A manhole guard comprising a base formed of a plurality of separable parts provided with vertically disposed sockets, a plurality of uprights each formed of a tubular post whose lower end is telescopically positioned in one of said sockets and of an upwardly inclined tubular beam having a pin in its outer end telescopically positioned in the post of an adjacent upright, and a gate section formed of a tubular post and an upwardly inclined beam having at its outer end a downwardly extending pin telescopically received by the tubular post of an adjacent upright for pivotally supporting the gate section.

8. A manhole guard comprising a base, a superstructure connected to the base, and a screen within the base for covering a manhole, said screen comprising a plate detachably connected to said base, a centrally disposed screen section pivotally attached to said plate, and wing screen sections pivotally attached to the sides of said central section.

9. A manhole guard comprising a base, a superstructure formed of a plurality of uprights detachably connected to the base; and a screen within the base formed of a plate detachably connected to said base, a central screen section pivotally attached to said plate, and wing screen sections respectively pivotally attached to the sides of said central section.

WILBUR W. STEVENSON.
